UNITED STATES PATENT OFFICE.

CHARLES FRANCIS JENKINS, OF WASHINGTON, DISTRICT OF COLUMBIA.

AIRPLANE STOP.

Application filed May 21, 1927. Serial No. 193,258.

This invention relates to airplanes, and has for its principal object devices for bringing an airplane to a stop promptly after touching the ground.

5 Until now the method of landing an airplane consists of shutting off the motor and gliding down until the wheels and tail-skid touch the ground and then trusting to fortune that the machine will run down before 10 it crashes into some other machine, or an obstruction, or into a ditch and noses over.

Every other transport vehicle has means for stopping it at will; the automobile has brakes which grip the solid road; the motor 15 boat, which rides on a liquid medium, stops by reversing the rotation of its propeller.

The airplane moves within the fluid medium which supports it in flight. But as it is supported only because of its speed it is 20 not safe to use a reversing propeller until the machine touches the ground. Nor are 25 brakes permissible because it noses the machine over, smashing up things.

It is to prevent these sources of danger 25 while retaining the controlled stop of reversed blades that this invention aims.

Not only will this mechanism permit stopping the plane in very restricted spaces at 30 will and with as much confidence as if it were a motor boat, but reversing the propeller blades after touching the deck of an airplane carrier would greatly facilitate 35 landing on "mother ships" at sea.

And the ability to stop quickly at will, 35 would, on occasions, prevent smashing up the plane in a delayed take-off, which has already been the cause of a number of pilot and passenger fatalities.

With this and other objects in view the 40 invention consists in the novel details of construction and combinations of parts more particularly pointed out in the claims.

Referring to the accompanying drawings forming a part of this specification, in which 45 like numerals designate like parts in all of the figures:

Fig. 1 is an airplane; Fig. 2 the tail-skid therein; Fig. 3 the propeller-motor section of the plane; and Fig. 4 the blade rotating 50 lever and lock therefor.

In the several figures, A is a propeller, the blades of which may be rotated about their longitudinal axis; B a collar slidable along the engine shaft, and connected by 55 links C to levers D on the hub-end of each blade; E a loose ring in a groove on collar

B, which advances or retracts the collar to partially rotate the blades to give them a different angular attack on the air; F a connecting rod from ring E to the hand lever G, which is in two parts. The two parts of the hand lever are pivoted at H and one of the parts, G', has a notch J in the lower, quadrant-shaped end of it to engage with a latch K. This latch is pivoted at L and has 60 attached thereto rods M and N, one of which, N, is fastened to the tail-skid P, and the other, M, attached to some part of the landing gear truck, R, which, as usual, supports the plane on springs, i. e., springs between 65 truck and fuselage.

S is a safety block on the lower end of lever G, which prevents the latch K from being pulled out by the landing gear until the block is moved from under the latch 70 when lever G is pushed forward. Each of the rods M and N has a spring end Z, so that the shock of landing does not damage the reversing gear before the lever can be moved.

The displacement of the safety block S is 75 the first result of the movement of the hand lever G. This forward movement of the lever also brings the pin T on the lever against one of the detents on the upper end of the locked part of the lever, and further 80 movement partially rotates the blades of the propeller. The "further movement" referred to is possible only when the lever is 85 unlocked by the landing gear, either the tail-skid of the truck, or both, coming into contact with the ground.

Such setting of the blades "in reverse" 90 renders the propeller effective in stopping the machine when the engine is turned up to such speed as circumstances may require.

In these specifications the word ground 95 is used to mean the landing surface upon which the plane comes to rest, and obviously, may be the surface of water, the deck of a ship, an elevated landing platform, or the like.

What I claim is—

1. The combination, in an airplane, of a 105 motor therein, a supporting landing gear therefor, a propeller driven by said motor, reversing gear for said propeller, and means for preventing the use of said propeller-reversing gear except when said supporting gear contacts with the ground.

2. The combination, in an airplane, of a 110 motor therein, a supporting landing gear therefor, a propeller driven by said motor,

reversing gear for said propeller, and means for preventing the use of said propeller-reversing gear until after said airplane makes contact with the ground.

5 3. The combination, in an airplane, of a motor therein, a supporting landing gear therefor, a propeller driven by said motor, reversing gear for said propeller, and means for preventing the use of said propeller-reversing gear until said airplane rests on the ground.

4. The combination, in an airplane, of a motor therein, a supporting landing gear therefor, a propeller driven by said motor, reversing gear for said propeller, means for locking said reversing gear, and spring

means for connecting the landing gear to the locking means to unlock the same when the landing gear contacts with the ground.

5. The combination, in an airplane, of a 20 motor therein, a supporting landing gear therefor, a propeller driven by said motor, reversing gear for said propeller, means for locking said reversing gear, spring means for connecting the landing gear to the locking means to unlock the same when the landing gear contacts with the ground, and means for preventing the unlocking of the locking means during the take-off.

In testimony whereof I have affixed my 30 signature.

CHARLES FRANCIS JENKINS.
